US00D614408S

(12) **United States Design Patent**
Koenig

(10) **Patent No.:** **US D614,408 S**
(45) **Date of Patent:** **** Apr. 27, 2010**

(54) **PATTERN FOR A SHEET**

(75) Inventor: **John William Koenig**, Cincinnati, OH
(US)

(73) Assignee: **The Procter & Gamble Company**,
Cincinnati, OH (US)

(**) Term: **14 Years**

(21) Appl. No.: **29/308,449**

(22) Filed: **Jun. 18, 2008**

(51) LOC (9) Cl. **05-06**

(52) U.S. Cl. **D5/57; D5/53**

(58) **Field of Classification Search** D5/1,
D5/2, 3, 7, 11, 16, 19, 25, 47, 52, 53, 57,

FIG. 2

UNITED STATES PATENT AND TRADEMARK OFFICE
CERTIFICATE OF CORRECTION

PATENT NO. : D614,408 S
APPLICATION NO. : 29/308449
DATED : April 27, 2010
INVENTOR(S) : Koenig

Page 1 of 4

It is certified that error appears in the above-identified patent and that said Letters Patent is hereby corrected as shown below:

The title page, showing an illustrative figure, should be deleted and substitute therefor the attached title page.

In the Drawings

Delete drawing sheets 1-2, and substitute therefor the Drawing Sheets, consisting of FIGS. 1-2,
As shown on the attached pages.

Signed and Sealed this
Fifteenth Day of April, 2014

Michelle K. Lee
Deputy Director of the United States Patent and Trademark Office
